UNITED STATES PATENT OFFICE.

FRANK R. ARTHUR, OF MOUNTAIN VIEW, CALIFORNIA.

AIR HEATER.

Application filed June 2, 1924. Serial No. 717,269.

To all whom it may concern:

Be it known that I, FRANK R. ARTHUR, a subject of the King of Great Britain, and a resident of Mountain View, in the county of 5 Santa Clara and State of California, have invented certain new and useful Improvements in Air Heaters, of which the following is a specification.

One object of the present invention is to 10 provide a heater of the character indicated that will quickly and effectively heat a large volume of air with a minimum consumption of fuel.

Another object of the invention is to provide 15 a heater of the character indicated in which the path of travel of the heated gases resulting from the burning of fuel is so arranged relative to that of the air to be heated that substantially all of the heat of said 20 heated gases is extracted therefrom and absorbed by the air passing thereby.

It is a further object to provide a device 25 in which some of the passages through which the heated gases pass are so constructed as to quickly transfer the heat from the heated gases to the air passing thereby, and in which some of the passages are so constructed as to store up heat for a relatively long period of time.

Finally, it is an object to provide a device 30 of the character indicated that will be simple in form and construction, economical to manufacture, and highly efficient in its practical application.

In the drawing:—

Figure 1 is a vertical transverse section through my improved air heater.

Figure 2 is a section on line 2—2 of Figure 1.

Referring more particularly to the drawing, I show an annular chamber 1 formed of two cast iron plates as 2 and 3 having opposed annular flanges 4 and 5 formed thereon. These flanges 4 and 5 form shoulders against which is arranged an annular sheet-iron element 6 forming a side wall for the chamber, the three parts 2, 3 and 6 being securely bound together by bolts 7.

In the center of plate 2 is an opening 8 45 through which the products of combustion are discharged into chamber 1 by any suitable burner 9.

In the center of plate 3 is an annular opening 10 provided with upstanding flange 11 55 interiorly threaded as at 12. Radially arranged and equally spaced about central

opening 10 are a plurality of oval openings 13, each of said openings being provided with an upstanding flange as shown at 14.

At 15 I show a third cast-iron plate provided with a central opening 16 and radially arranged openings 17 provided with depending flanges 18, these openings 16 and 17 being exactly the same in number, size and conformation as the openings 10 and 13 in plate 3, and the flanges 18 being arranged in opposed relation to flanges 14 on plate 3.

At 19 is shown a wrought or cast-iron pipe threaded into flange 11 around opening 10 in plate 3 and passing through opening 16 in plate 15. Pipe 19 is threaded upon its upper end to engage nuts 20 and 21 whereby to securely fasten the parts together.

The opposing flanges 14 and 18 around openings 13 and 17 in plates 3 and 15 are 75 connected by sheet-iron pipes 22, these pipes fitting snugly over said flanges and preferably being welded thereto.

A fourth cast-iron plate is shown at 23 provided with a depending flange 24 arranged in opposed relation to upstanding flange 25 on plate 15. Seated against flanges 24 and 25 is a sheet-iron element 26 forming the side wall of annular chamber 27, the two parts 15 and 23 being secured together by 85 bolts 28.

Arranged on the upper surface of plate 15 is an upstanding flange 29 spaced a distance from wall 26 and yet enclosing the radially arranged openings 17, this flange having a 90 height exactly one-half the height of chamber 27. Flange 29 is separated at one point to make an opening 30, one portion of the flange being bent inwardly at an angle as at 31.

Depending from the under side of plate 23 is an annular flange 32 corresponding exactly in size and conformation to flange 29, the opposing edges of the two flanges contacting when the plates 15 and 23 are assembled 100 to form a chamber 33.

In the center of the plate 23 is formed an opening 34 provided with an upstanding flange 35 threaded to receive a cap 36 which has a mica window 37 therein.

A pipe for carrying away waste products of combustion is provided at 38 and is connected to chamber 27 at 39. Surrounding the structure above described is a shell 40 discharging through a perforated floor plate 41 into the room to be heated.

In operation, the moment the gas is lighted

at the burner 9 the flame and heated gases and smoke fill chamber 1 and pass through pipes 19 and 22 into chamber 33, then discharge through opening 30 into chamber 27 where they pass around to pipe 38 and thence to the atmosphere, the direction of travel being indicated by small arrows.

Since parts 6, 22 and 23 are of thin metal the air surrounding these parts is quickly heated and a circulation of warm air into the room above is immediately set up. As the cast-iron parts 2, 3, 15 and 23 become heated they, of course, assist in heating the air passing through shell 40. When the required temperature has been reached in the room the flame at 9 may be lowered because a great deal of the excess heat required to quickly heat the air in shell 40 has been stored up in plates 2, 3 and 15 and 23, and is now slowly released to maintain the air passing through shell 40 at the required temperature.

By passing the heated gases through the several pipes and then through and entirely around chamber 33 before they are discharged from pipe 38 practically all of the heat units are extracted therefrom, rendering the device highly efficient in its practical application.

30 The central column of heated gases discharging into the upper chamber 33 causes the columns discharging from the several pipes 22 to eddy in said upper chamber, thereby bringing them in contact with every portion of the walls of said chamber.

40 This device is simple in construction, economical to manufacture, and provides a large amount of heating surface relative to the cross-sectional area of the shell in which it is placed.

45 It is to be understood, of course, that while I have herein shown and described but one specific embodiment of my invention, changes in form, construction and method of operation may be made within the scope of the appended claims.

I claim:

1. In a heater of the character indicated, 50 a pair of vertically spaced chambers, an axially arranged tube connecting said chambers, a plurality of tubes spaced about said central tube and connecting said chambers, a chamber arranged within the upper chamber and communicating therewith, and an outlet from said upper chamber at a point remote from its communication with said inner chamber.

60 2. In a heater of the character indicated, a pair of vertically spaced chambers, having top and bottom walls adapted to store heat and side walls adapted to quickly transmit heat therethrough, an axially arranged tube

connecting said chambers, a plurality of tubes spaced about said central tube and connecting said chambers, a chamber arranged within the upper chamber and communicating therewith, and an outlet from said upper chamber at a point remote from its communication with said inner chamber. 65

3. In a heater of the character indicated, 70 a pair of vertically spaced chambers having top and bottom walls adapted to store heat and side walls adapted to quickly transmit heat therethrough, an axially arranged tube connecting said chambers, a plurality of tubes of low heat storing characteristics spaced about said central tube and connecting said chambers, a chamber arranged within said upper chamber and communicating therewith, and an outlet from said upper chamber at a point remote from its communication with said inner chamber. 75

4. In a heater of the character indicated, 80 a pair of vertically spaced chambers having top and bottom walls of cast metal and side walls of sheet metal, an axially aligned tube connecting said chambers, a plurality of sheet metal tubes spaced about said central tube and connecting said chambers, a chamber arranged within said upper chamber and communicating therewith, and an outlet from said upper chamber at a point remote from its communication with said inner chamber. 85

5. In a heater of the character indicated, 90 a pair of vertically spaced chambers, the lower chamber comprising top and bottom elements of cast metal spaced by a side wall of sheet metal, and the upper chamber comprising top and bottom cast metal elements spaced by a side wall of sheet metal and having opposed flanges arranged thereon a distance within said spacing wall and arranged to contact at their opposing edges when assembled and having a passage therethrough, an outlet arranged in said upper chamber at a point remote from said passage, an axially arranged tube connecting said chambers, and a plurality of tubes spaced about said central tube and connecting said chambers. 100

6. In a heater of the character indicated, 110 a pair of vertically spaced chambers, an axially arranged tube connecting said chambers, a plurality of tubes spaced about said central tube and connecting said chambers, a chamber arranged within the upper chamber and communicating therewith and encompassing the ends of the tubes connected to the said upper chamber, and an outlet from said upper chamber at a point remote from its communication with said inner chamber. 115
